UNITED STATES PATENT OFFICE.

ALBERT KOUNOVSKY, OF WOOD LAKE, NEBRASKA.

TRUNDLING TOY.

1,097,102.

Specification of Letters Patent. Patented May 19, 1914.

Application filed November 26, 1913. Serial No. 803,243.

To all whom it may concern:

Be it known that I, ALBERT KOUNOVSKY, a citizen of the United States, residing at Wood Lake, in the county of Cherry and 5 State of Nebraska, have invented certain new and useful Improvements in Trundling Toys, of which the following is a specification, reference being had to the accompanying drawings.

10 This invention relates to new and useful improvements in toys and more particularly to a trundling toy and the primary object of the invention is to provide a device of this character which may be pushed about from 15 place to place by children as an amusement device as well as a means for exercising.

A further object of the invention resides in providing a toy which is simple and durable in construction, inexpensive to manufacture and one which will be efficient in use.

20 With these and other objects in view, the invention consists in the novel features of construction, combination and arrangement 25 of parts as will be hereinafter referred to and more particularly pointed out in the specification and claims.

In the accompanying drawing form a part 30 of this application, Figure 1 is a plan view 35 of a device constructed in accordance with my invention a portion thereof being in perspective. Fig. 2 is a fragmentary perspective view thereof. Fig. 3 is a section as seen on line 3—3, Fig. 1. Fig. 4 is a similar view as seen on line 4—4, Fig. 1. Fig. 5 is a perspective view of the spring rod of the device removed. Fig. 6 is a diagrammatic view of the device; and Fig. 7 is a similar view showing the various positions of the 40 axle in the operation of the device.

In describing my invention, I shall refer to the drawing in which similar reference characters designate corresponding parts throughout the several views and in which 45 I indicates an axle upon the ends of which are rotatably mounted the wheels 2, said wheels being prevented from moving outwardly on the axle by means of the collars 3 carried on said axle. This axle may be formed of any 50 desired material and is looped, intermediate of its ends to form an eye or the like 4, the purpose of which will presently appear.

An additional bar 5 is provided, the ends 55 of which are looped around the axle 1 as shown at 6 to form substantially a retaining means for the movement of the wheels 2 in-

wardly on said axle. This additional bar is also looped intermediate of its ends to form an eye 7, which aligns with the eye 4 on the axle and disposed through these aligning eyes, 60 is the outer end of a steering rod 8. This rod is prevented from longitudinal movement through the eyes by means of the collars 9 and 10, the former being arranged in connection with the eye 7 and the latter on the outer end of the rod in connection with the eye 4. This rod 8 is bent angularly at the point at which the collar 9 is provided, thus providing an angular steering rod and the outer end of this rod 8 is designed to 65 form substantially a steering wheel 11.

70 From the above description of the construction of the device, it will be seen that the same may be pushed about from place to place as an amusement device for children. In view of the angular construction 75 of the rod, it will be seen that the axle with the wheels thereon may be guided in any direction in which the steering wheel 11 is turned, in imitation of an automobile steering construction. Such devices, it will be seen, will not alone afford an amusement as 80 a toy but also perform the function of an exercising device for those using the same.

85 From the foregoing it will be seen that I have provided a simple, inexpensive and efficient means for carrying out the objects of the invention and while I have particularly described the elements best adapted to perform the functions set forth, it is obvious 90 that various changes in form, proportion and in the minor details of construction may be resorted to without departing from the spirit or sacrificing any of the principles of 95 the invention.

Having thus described this invention, what I claim is:

1. A trundling toy comprising a wheeled axle, bearings formed on said axle, a rod loosely mounted at one end thereof in said bearings, said rod being bent angularly from 100 said bearings to its outer end, whereby said toy may be guided upon rotation of said rod.

2. A trundling toy comprising an axle, wheels rotatably mounted thereon, bearings 105 formed on the axle, and a rod loosely mounted at one end thereof in said bearings, and bent angularly from said bearings to the outer end thereof.

3. A trundling toy comprising an axle, 110 wheels rotatably mounted thereon, a brace spaced for the greater portion of its length

from the axle for connection at its ends adjacent said wheels, bearings formed centrally on said brace and axle, and a rod loosely mounted at one end thereof in the 5 bearings and bent angularly from said bearings to the outer end thereof.

4. A trundling toy comprising an axle, wheels rotatably mounted on the outer end thereof, a brace spaced for the greater portion 10 of its length from said axle and secured at its ends to the latter to form a partial retaining means for said wheels on the axle, bearings formed centrally on said brace and axle, and a rod loosely mounted at one end 15 thereof in said bearings and bent angularly from the bearings to the outer end of the same.

5. A trundling toy comprising an axle looped intermediate of its ends to form an 20 eye, wheels rotatably mounted on the outer ends thereof, a brace secured at its ends to the axle and spaced for the greater portion of its length from the latter, said brace being looped for the greater portion of its

length and provided with an eye alining 25 with the first mentioned eye, a rod loosely mounted at one end thereof in said eyes and bent angularly from the latter to the outer end thereof.

6. A trundling toy comprising an axle 30 looped intermediate of its ends to form an eye, wheels rotatably carried on the outer ends of said axle, a brace secured at its ends to said axle to form a partial retaining means for the wheels thereon, said brace being looped intermediate of its ends to form an eye alining with the first mentioned eye, and a rod loosely mounted at one end thereof in said alining eyes and bent angularly 35 from the eye on said brace to the outer end 40 of said rod.

In testimony whereof I hereunto affix my signature in the presence of two witnesses.

ALBERT KOUNOVSKY.
